DESIGN FOR A MEDAL

John Inquisitore, New York, N. Y.

Application September 16, 1939, Serial No. 87,259

Term of patent 3½ years

To all whom it may concern:

Be it known that I, John Inquisitore, a citizen of the United States, residing at 3941 Barnes Avenue, city of New York, county of the Bronx, and State of New York, have invented a new, original, and ornamental Design for a Medal, of which the following is a specification, reference being had to the accompanying drawing, forming part thereof.

Fig. 1 is a front elevational view of a medal showing my new design; and

Fig. 2 is a rear elevational view thereof.

I claim:

The ornamental design for a medal, as shown.

JOHN INQUISITORE.
